UNITED STATES PATENT OFFICE

2,049,171

COAL CUTTING APPARATUS

Charles F. Osgood, Claremont, N. H., assignor to
Sullivan Machinery Company, a corporation of
Massachusetts

Application July 24, 1935, Serial No. 32,924

21 Claims. (Cl. 262—33)

This invention relates to coal cutting apparatus, and more particularly to improvements in a reciprocating flexible cutter particularly adapted to use with a hoisting mechanism.

An object of this invention is to provide an improved coal cutting apparatus having improved cutting means of the reciprocating type. Another object is to provide an improved coal cutting device whereby a relatively narrow kerf may be rapidly cut in the coal when the aforesaid device is reciprocated rapidly back and forth across the coal seam, in the manner of a cross cut saw. A further object is to provide an improved coal cutting device of the reciprocating, cable operated type operatively connected to the cables of a hoisting mechanism whereby the hoisting mechanism may operate the cutting device with a reciprocating motion across the coal seam. Yet another object is to provide in a cutting device of the above character, improved pivotal mounting means for the cutting elements. These and other objects will, however, hereinafter more fully appear.

In the accompanying drawing there are shown for purposes of illustration three forms which this invention may assume in practice.

In this drawing,—

Fig. 1 is a somewhat diagrammatic view showing the preferred illustrative form of the improved cutting device and the associated hoisting mechanism.

Fig. 2 is an enlarged view partially in side elevation and partially in longitudinal section of the improved cutting device shown in Fig. 1.

Fig. 3 is a cross sectional view taken substantially on line 3—3 of Fig. 2.

Fig. 4 is a view in longitudinal section showing a modified form of cutter mounting.

Fig. 5 is a view in longitudinal section showing still another form of cutter mounting.

Fig. 6 is a perspective view showing one of the pivoted cutter blocks.

In the illustrative construction shown in Figs. 1 to 3, inclusive, and Fig. 6, the improved reciprocating cutter is generally designated 1, the cable winding mechanism 2 and the cutter actuating cables 3 and 4. The cable winding mechanism 2 includes a pair of relatively rotatable, power operated cable winding drums 5 and 6 operated and controlled by a suitable reverse control mechanism 7 by means of which the drums 50 may be oppositely rotated in unison so that as

one drum is winding up its cable, the other drum will be paying out its cable.

The improved reciprocating cutter is particularly adapted to use in pillar cutting in accordance with the "panel" system of mining and is especially designed to use in cutting pillars between rooms or entries. In this instance, the pillar or "panel" is indicated at 8 and the tunnels or galleries extending along the sides of the pillar are indicated at 9, while the cross connecting 10 entries are indicated at 10.

The cables 3 and 4 are connected in any suitable manner to the ends of the improved reciprocating cutter 1, the latter being disposed across the pillar 8 and along the sides thereof in the manner shown in Fig. 1. Each of the cables 3 and 4 is carried along the entry 9 in which it is located to the cross connecting entry 10 at the end of the pillar 8 remote from the end upon which the cutter is operated. Suitable temporary posts 15 or columns 11 are located at the opposite sides of the entry 10, to which pulley blocks or sheaves 12 are attached and through which the cables 3 and 4 run to make a right angle turn for connection with the winding drums 5 and 6 of the hoisting mechanism. By arranging the cable guiding pulleys 12 at different locations and by changing the stroke and length of the cutter, it will be evident that pillars of varying widths may be expeditiously cut.

So that the operator may determine the exact location of the cutter within the cut, suitable markers 13 and 14 are adjustably attached, as by suitable clamps, to the cables 3 and 4, respectively, at points spaced equally from the ends of the cutter, and these markers are located adjacent the cable winding mechanism 2 within the sight of the operator so that the operator may readily ascertain the exact position of the cutter with respect to the coal seam so as to obtain the proper cutting strokes.

The reversing mechanism 7 is of the proper character to effect reversal of the direction of rotation of the drums 5 and 6 at the proper intervals so that the cutter 1 will be reciprocated rapidly back and forth, in the manner of a cross cutting saw, across the coal seam in the pillar.

Now referring to the illustrative form of the improved cutting device, as shown in Figs. 2, 3 and 6, it will be observed that the same is in the form of a flexible actuating element, preferably of articulated construction, herein comprising a length of chain 15. This chain comprises rod-like link elements 16 in the form of bolts having spaced end collars 17, 17 and eye-like end por-

tions 18, 18, and pivotally connected together in series by links 19. Journalized on the rod-like portion 16 of each of the bolts is a rotatable block 20 having a hub portion 21 journalized on the rod between the collars 17, 17, and, projecting radially from the hub portion 21, a series of radial arm-like supports 22, each having pivotally mounted thereon at 23 a cutter block 24. The pivotal axes of the cutter blocks 24 are arranged at right angles to lines extending radially with respect to the axis of rotation of the block 21 and each is provided with a pair of suitable sockets for receiving reversely positioned cutter bits 25, each of the bits being held within its socket by means of a usual set screw 26. The arm-like portions 22 of the rotatable blocks 20 are cut away at 27 to receive the pivoted cutter blocks, and are formed with end abutment surfaces 28 and 29 with which the cutter blocks are engageable in their opposite positions about their pivots. It will thus be seen that the blocks 20 are rotatable about the longitudinal axis of the reciprocating cutter and that the cutter bits, by means of their pivoted mountings, are automatically reversed as the cutter is reciprocated back and forth.

In the modified form of construction shown in Fig. 4, the pivoted cutter blocks are mounted on rotatable blocks 30 each having secured within its bore 31 a bearing sleeve 32 having outwardly flared ends 33, and these blocks are rotatably mounted on a flexible actuating element in the form of a wire rope or cable 34. Mounted on the cable at the opposite sides of the rotatable blocks and engaging the flared ends of the bearing sleeves are bearing washers 35, 35, while the blocks are maintained in spaced relation on the cable 34 by means of spacing sleeves 36. In the modified form of construction shown in Fig. 5, the actuating cable 34 has mounted thereon sleeves 37 on which are rotatably mounted blocks 38 on which the pivoted cutter blocks are mounted. The sleeves 37 are maintained in spaced relation by spacing sleeves 38. In this instance, the blocks 38 have pivotally mounted thereon at 39 cutter blocks 40, each carrying a cutter bit 41, and the cutters on one rotatable block face in one direction, while the cutters on the next succeeding block face in the opposite direction. The arm-like portions 42 of the block 38 are provided with abutment surfaces 43 and 44, the cutter blocks being engaged with the abutment surfaces 43 during cutting and with the abutment surfaces 44 when in their inoperative position. The swinging cutter blocks are similarly mounted on the blocks 30 shown in Fig. 4. Otherwise the forms of the invention shown in Figs. 4 and 5 are similar to that described above.

The operation of the improved reciprocating cutter will be readily understood from the foregoing description, it being noted that as the cutter is moved by the cables 3, 4 of the hoisting mechanism 2, the pivotal connections of the cutter blocks with the rotatable blocks enables the cutters to tilt on both opposite directions of movement, thereby enabling the cutter bits to reverse automatically as the cutter is reciprocated back and forth across the coal seam. As the cut progresses and brings the front pulleys of the cutter actuating cables too near the guide pulleys, the posts 11 may be removed and the entire mechanism placed further back in the entry.

As a result of this invention, it will be noted that an improved reciprocating cutter is provided which is operated by means located at a

point remote from the cutting face, thereby diminishing the possibility of injury to the operator and damage to the machine upon falling of the roof. It will further be noted that an improved reciprocating cutter is provided consisting of a flexible actuating element having rotatably mounted thereon blocks on which the reversible cutter blocks are pivotally mounted so that when the cutter is moved in one direction, one set of cutter bits acts to cut the kerf, or when the cutter is moved in the opposite direction, another set of cutting bits acts to cut the kerf, so that as the cutter is reciprocated back and forth across the coal face, several cutter bits are always effective to perform the cutting function. It will further be noted that the improved reciprocating cutter is composed of elements which are extremely simple and rugged in design and which may be manufactured at a minimum of expense. Other uses and advantages of the improved reciprocating cutter will be clearly apparent to those skilled in the art.

While I have in this application specifically described three forms which my invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. In a reciprocating cutter, a series of rotatable blocks mounted to turn about the longitudinal axis of the cutter, and a plurality of cutter blocks pivotally mounted on each of said rotatable blocks for swinging movement relative thereto and to each other, each pivoted cutter block carrying a cutter bit.

2. In a reciprocating cutter, a series of rotatable blocks mounted to turn about the longitudinal axis of the cutter, and a plurality of cutter blocks pivotally mounted on each of said rotatable blocks for swinging movement relative thereto and to each other, each pivoted cutter block carrying reversely positioned cutter bits.

3. In a reciprocating cutter, a flexible actuating element comprising a series of rod-like elements disposed longitudinally of said flexible actuating element and pivotally connected by links, a block rotatably mounted on each rod-like element, and a plurality of cutter blocks pivotally mounted on each of said rotatable blocks, each pivoted cutter block carrying a cutter bit.

4. In a reciprocating cutter, a flexible actuating element comprising a series of rod-like elements disposed longitudinally of said flexible actuating element and pivotally connected by links, a block rotatably mounted on each rod-like element, and a plurality of cutter blocks pivotally mounted on each of said rotatable blocks, each pivoted cutter block carrying reversely positioned cutter bits.

5. In a reciprocating cutter, a flexible actuating element comprising rod-like elements disposed longitudinally of said flexible actuating element and pivotally connected by links, blocks rotatably mounted on each of said rod-like elements, a plurality of cutter blocks pivotally mounted on each of said rotatable blocks, each pivoted cutter block carrying a cutter bit, and stop means on said rotatable blocks for limiting swinging movement of said cutter blocks in one direction.

6. In a reciprocating cutter, a flexible actuating element comprising rod-like elements disposed

- longitudinally of said flexible actuating element and pivotally connected by links, blocks rotatably mounted on each of said rod-like elements, a plurality of cutter blocks pivotally mounted on each of said rotatable blocks, each pivoted cutter block carrying a cutter bit, and stop means on said rotatable blocks for limiting swinging movement of said cutter blocks in opposite directions.
7. In a reciprocating cutter, a flexible actuating element comprising rod-like elements disposed longitudinally of said flexible actuating element and pivotally connected by links, blocks rotatably mounted on each of said rod-like elements, a plurality of cutter blocks pivotally mounted on each of said rotatable blocks, each pivoted cutter block carrying reversely positioned cutter bits, and stop means on said rotatable blocks for limiting swinging movement of said cutter blocks in one direction.
- 10 8. In a reciprocating cutter, a flexible actuating element comprising rod-like elements pivotally connected by links, blocks rotatably mounted on each of said rod-like elements, a plurality of cutter blocks pivotally mounted on each of said rotatable blocks, each pivoted cutter block carrying reversely positioned cutter bits, and stop means on said rotatable blocks for limiting swinging movement of said cutter blocks in opposite directions.
- 15 9. In a reciprocating cutter, a flexible actuating element in the form of a wire rope, blocks rotatably mounted on said wire rope and turnable thereon relative thereto and to each other on axes extending longitudinally of said rope, spacing elements on said wire rope between said blocks for maintaining said blocks in spaced relation along the length of the wire rope, and a plurality of cutter blocks pivotally mounted on each of said rotatable blocks, each pivoted cutter block carrying a cutter bit.
- 20 10. In a reciprocating cutter, a flexible actuating element in the form of a wire rope, blocks rotatably mounted on said wire rope and turnable thereon relative thereto and to each other on axes extending longitudinally of said rope, spacing elements on said wire rope between said blocks for maintaining said blocks in spaced relation along the length of the wire rope, a plurality of cutter blocks pivotally mounted on each of said rotatable blocks, each pivoted cutter block carrying a cutter bit, and stop means on said rotatable blocks for limiting swinging movement of said pivoted cutter blocks in one direction.
- 25 11. In a reciprocating cutter, a flexible actuating element in the form of a wire rope, blocks rotatably mounted on said wire rope and turnable thereon relative thereto and to each other on axes extending longitudinally of said rope, spacing elements on said wire rope between said blocks for maintaining said blocks in spaced relation along the length of the wire rope, a plurality of cutter blocks pivotally mounted on each of said rotatable blocks, each pivoted cutter block carrying a cutter bit, and stop means on said rotatable blocks for limiting swinging movement of said pivoted cutter blocks in opposite directions.
- 30 12. In a reciprocating cutter, a flexible actuating element in the form of a wire rope, bearing sleeves mounted on said wire rope, spacing means on said wire rope for maintaining said bearing sleeves in spaced relation along the length of the wire rope, a block rotatably mounted on each of said bearing sleeves, and a plurality of cutter blocks pivotally mounted on each of said rotatable blocks, each pivoted cutter block carrying a cutter bit.
- 35 13. In a reciprocating cutter, a flexible actuating element in the form of a wire rope, bearing sleeves mounted on said wire rope, spacing means on said wire rope for maintaining said bearing sleeves in spaced relation along the length of the wire rope, a block rotatably mounted on each of said bearing sleeves, a plurality of cutter blocks pivotally mounted on each of said rotatable blocks, each pivoted cutter block carrying a cutter bit, and means on said rotatable blocks for limiting swinging movement of said cutter blocks in one direction.
- 40 14. In a reciprocating cutter, a flexible actuating element in the form of a wire rope, bearing sleeves mounted on said wire rope, spacing means on said wire rope for maintaining said bearing sleeves in spaced relation along the length of the wire rope, a block rotatably mounted on each of said bearing sleeves, a plurality of cutter blocks pivotally mounted on each of said rotatable blocks, each pivoted cutter block carrying a cutter bit, and means on said rotatable blocks for limiting swinging movement of said cutter blocks in opposite directions.
- 45 15. In a reciprocating cutter, a flexible actuating element, a series of blocks rotatably mounted at spaced points along the length of said actuating element and rotatable relative to each other and to said flexible actuating element upon axes extending longitudinally of said flexible actuating element, and cutter bits pivotally mounted on said rotatable blocks to swing in planes extending in the direction of reciprocatory motion of the cutter.
- 50 16. In a reciprocating cutter, a series of rotatable blocks mounted in turn independently of each other about axes extending in the direction of reciprocation of the cutter, and a plurality of cutters pivotally mounted on each block to swing relative thereto in planes parallel with the block rotation axes.
- 55 17. In a reciprocating cutter, a flexible actuating element, a series of blocks journaled for rotation at spaced points along the length of said actuating element and rotatable relative to each other and to said flexible actuating element upon axes extending longitudinally of said flexible actuating element, and reversible cutter bits pivotally mounted on said rotatable blocks to swing with respect thereto in planes extending in the direction of reciprocation of the cutter.
- 60 18. In a reciprocating cutter, a series of rotatable blocks mounted to turn independently of each other about axes extending in the direction of reciprocation of the cutter, and reversely positioned cutters pivotally mounted on each rotatable block to swing relative thereto in planes parallel to the block rotation axes.
- 65 19. In a reciprocating cutter, a flexible actuating element including a series of articulated rod-like elements, a block journaled for rotation on each rod-like element, and a plurality of cutters pivotally mounted on each rotatable block to swing with respect thereto in planes parallel with the block rotation axes.
- 70 20. In a reciprocating cutter, a flexible actuating element in the form of a wire rope, blocks journaled for rotation on said wire rope and turnable thereon relative thereto and to each other, spacing elements maintaining said blocks in spaced relation along the length of the wire rope, and cutters pivotally mounted on each block to

swing relative thereto in planes parallel with the block rotation axes.

21. In a reciprocating cutter, a flexible actuating element in the form of a wire rope, bearing sleeves mounted on said rope, spacing means on said wire rope for maintaining said bearing sleeves in spaced relation along the length of the wire

rope, blocks journaled for rotation on said bearing sleeves respectively, and cutters pivotally mounted on said blocks to swing with respect thereto in planes parallel with the block rotation axes.

CHARLES F. OSGOOD.

CERTIFICATE OF CORRECTION.

Patent No. 2,049,171.

July 28, 1936.

CHARLES F. OSGOOD.

It is hereby certified that error appears in the printed specification of the above numbered patent requiring correction as follows: Page 3, second column, line 38, claim 16, for the word "in" read to; and that the said Letters Patent should be read with this correction therein that the same may conform to the record of the case in the Patent Office.

Signed and sealed this 1st day of December, A. D. 1936.

Henry Van Arsdale

(Seal)

Acting Commissioner of Patents.
